UNITED STATES PATENT OFFICE.

CONRAD REHBEIN, OF DETROIT, MICHIGAN.

MACHINE FOR SLITTING AND BENDING SHEET METAL.

1,118,232.

Specification of Letters Patent.

Patented Nov. 24, 1914.

Application filed March 18, 1914. Serial No. 825,466.

To all whom it may concern:

Be it known that I, CONRAD REHBEIN, a citizen of the United States, and a resident of Detroit, in the county of Wayne and State of Michigan, have invented a new and Improved Machine for Slitting and Bending Sheet Metal, of which the following is a specification.

This invention relates to means for feeding, slitting and bending portions of ribbons or bands of thin sheet metal at regular intervals, and its object is to provide a slitting and bending press that will accurately space the perforations and bent up portions of the material acted upon.

This invention consists of a positive feed for bands of sheet metal, comprising a clamp, a cam to slide the clamp along and a spring to return the clamp, a spring held plunger to close the clamp, and a slitting device formed of two parts, one of which is transversely grooved so that the tongues of metal produced thereby will remain connected to the main body of the ribbon and project upwardly therefrom.

This invention further consists in the details of construction set forth in the drawings and particularly pointed out in the claims.

In the accompanying drawings, Figure 1 is a front elevation of this improved machine. Fig. 2 is a plan of the support for the roll of metal ribbon to be slit and bent. Fig. 3 is a plan of the table and lower die. Fig. 4 is a front elevation of the upper and lower dies; the front of the latter being broken away to show the supporting springs of the stripper plate. Fig. 5 is a side elevation of the dies. Fig. 6 is a section on the line A—A of Fig. 5. Fig. 7 is a plan of the upper die. Fig. 8 is a transverse section of the dies at one of the stripper pins on a larger scale. Fig. 9 is a similar section through the bifurcated die. Fig. 10 is a perspective of the upper or female die. Fig. 11 is a perspective of the lower or male die. Fig. 12 is a perspective of a portion of the upper die. Fig. 13 is a perspective view of the finished material.

Similar reference characters refer to like parts throughout the several views.

The press shown in the drawings may be of any desired construction, as this improved mechanism may be attached to practically all types of vertical presses now on the market.

In Fig. 1, a stationary bed 1 is carried by the frame 2, which has guides 3 in which the vertically movable head 4 is slidable. Any desired means may be employed to move the head up and down, a shaft 5 and connecting rod 6 being shown, the parts being at the upper limit of their movement. On the bed 1 a table 7 may be rigidly secured or the two may be integral. Arms 8 extend to the right and carry small brackets 9 which support a shaft 10 on which the roll of sheet metal 11 of the proper width is mounted to turn freely. Bars 13 and 14 extend across between the arms 8, and are connected by the plate 15 above which the band 11 passes to the shear. Above the plate 15 are two adjustable guide bars 16 secured to the plate by means of the bolts 17. Springs 18 may be secured to these guide bars and bear on the band 11 to act as brakes and to prevent it from moving up and down. The head 4 carries a head plate 20, in which is mounted the vertically movable plunger 21 for closing the clamp, and to which are secured the cams 22 for moving the clamp forward. The plunger has a collar 23 to limit its downward movement with respect to the head plate. On the head plate is secured an elongated stirrup 24, in which the spring 25 is mounted on the stem 26 of the plunger. Above the stirrup may be mounted a second spring 27 that cushions the plunger when it is released, as hereinafter described. A nut 28 at the upper end of the stem receives the thrust of the spring 27. The feed-clamp is formed of two shoes 30, slideable between the inclined guides 31 secured to the table 7. These shoes may have contact members 32 to engage the screws 33 mounted in the cross bar 13. Springs 34, at the sides of the clamp, connect to the screws 35 on the shoe and to the screws 36 carried by the arms 8. An abutment 37 on each shoe engages the adjacent end of the upper plate 38, guided on the screws 39, and held spaced apart from the shoes by means of springs 40. The shoes and upper plate may be provided with gripping members 42, which may be of fiber, wood or hard rubber.

When the parts are as shown in Figs. 1 and 5, the band 11 is loose between the shoes and top plate of the clamp. When the head plate descends, the plunger 21 engages the top plate 38 and the spring 25 forces the plate 38 down until the members 42 firmly grip the band of metal. Immediately after

this, the cams 22 engage the shoes 30 and force the clamp forward, sliding it under the lower end of the plunger, and with it the band 11. It will be noticed that the cams 5 22 will always move the clamp to the predetermined position from a point determined by the screws 33. The amount the band is moved forward at each stroke of the press can therefore be accurately determined.

When the head plate 20 has reached the lower end of its movement, a small bolt 45, (Fig. 6) slideable in the housing 46, and normally held toward the plunger by the 15 spring 47, engages in a notch in the plunger, as indicated in Figs. 5 and 6. When the head plate rises, the plunger will be lifted free from the top plate 38 of the clamp, permitting the grippers 42 to separate. When 20 the cams 22 have risen sufficiently, the springs 34 will move back the clamp to the position shown in Fig. 1, where it will remain until the head of the press again descends.

25 On the upstroke of the head plate 20, a cam 77, mounted on the frame 2 will engage the finger 78 on the bolt 45, and just after the clamp has been moved back by the springs 34, the bolt 45 will be withdrawn, 30 permitting the spring 25 to force the plunger downward. At this time, the spring 27 acts as a cushion.

This machine is especially designed to produce a slotted strip or band of sheet 35 metal such as shown in Fig. 13, where great accuracy of spacing is required. The metal is to be used to form the radiating fins of cellular radiators adapted for automobiles, the fins being placed between and soldered 40 to thin wide tubes. These fins 50 connect to cross bars 51, which in turn connect to the longitudinal bars 52 and 53. The latter bar is bent longitudinally until two of the small lips 54 engage the adjacent end of 45 each fin 50, in which position they are soldered. The openings between these lips 54 constitute the apertures for the circulating air, the fins 50 extending horizontally into the current of air. The third longitudinal 50 bar 55 is bent to lie against the ends of the lips 54 parallel to the bar 53.

The band 11 passes over the stripper plate 55 and the support 57. The stripper plate is mounted on the springs 58 and is guided 60 on the pins 59. It is provided with one slot 60 for the long cutter 61 to form the fins 50 and another slot 64 to permit the passage of the bifurcated die 65.

The die holders 70 and 71 rest on the table 65 7 and grip the dies 61 and 65, being forced together by means of the wedge 72 and the inclined abutments 73 and 74. The upper die is preferably formed of three pieces, the body 66, the short die 67 and the plate 68.

65 The width of the slot between the plate 68

and the edge 69 is greater than the thickness of the cutter 61, as shown in Fig. 8, so that the fins 50 will remain attached to the cross bars 51. The short die 65 that forms the lips 54 co-acts with the female die 67. The outer edges of the upwardly extending shear members 81 engage the inner edges of the downwardly extending shear member 82 and the edges of the slot in the body 61 in which the die 67 is mounted, thus cutting 75 free the lips 54. At the same time, the blade 83 enters the groove between the shear members 81 and engages the unsevered portion of the metal between the lips 54, as shown in Fig. 9, thus properly bending these lips 80 in the groove between the members 81.

As shown in Fig. 4, the upper surface of the stripper plate is normally at the same height as the cutting edges of the shear members 61 and 81, and is preferably a short 85 distance above the level of the lower grippers 42. When the head plate and upper dies descend, the plunger 21 first forces the clamp to grip the band 11. The cams 22 then move the clamp and band forward one 90 space, and hold them there. The upper die then engages the band and stripper plate 56 and forces them down, the die 61 cutting free a fin 50 and the bifurcated die cutting out two lips 54. At the same time, the beveled lower edge of the plate 68 will 95 straighten the next previously formed fin 50, should that lean outwardly.

At the last portion of the stroke of the head, the stripper pins 86, mounted in the 100 body 66, as shown in Fig. 8 and indicated in Fig. 7, engage the band 11, and are compressed against the tension of the springs 87, held in place by the screw plugs 88. When the head rises, these pins will force 105 down the band 11 and disengage the fins 50 and lips 54 from the upper dies. The clamp is returned by the springs 14 to starting position and the machine is ready to go through the next cycle of its operation.

This device may be changed in many details by competent designers without departing from the spirit of my invention as expressed in the claims.

I claim:

1. In a slitting and bending machine for sheet metal, the combination of a spring mounted supporting plate for the sheet metal having perforations, a narrow slitting die extending up into one of the perforations, a second die extending up into another perforation and having a transverse groove in line with one side of the slitting die, a movable male die to co-act with the stationary dies, and means for feeding a band of sheet metal to said dies.

2. In a slitting and bending machine for sheet metal, the combination of a table, a spring mounted supporting plate for the sheet metal having perforations, a narrow

male slitting and bending die supported by the table and extending through said plate, a rectangular die mounted adjacent the slitting die and having a transverse groove in line with the rear side of the slitting die, and a female die movable toward and from the stationary dies and having shearing edges to co-act with the shearing edges of the stationary dies and a blade to extend 10 into the groove of the rectangular die.

3. In a slitting and bending machine for sheet metal, the combination of a frame, a table mounted thereon, a head vertically slidably in the frame, a clamp slidably 15 mounted on the table comprising upper and lower members between which the sheet metal may pass, springs to normally hold the members spaced apart, a plunger slidably mounted on the head, a spring to force 20 the plunger downwardly to press the members of the clamp together, a cam on the head to engage and move the clamp to feed the sheet metal, and dies to slit and bend the sheet metal.

25 4. In a slitting and bending machine for sheet metal, the combination of a frame, a table mounted thereon, a head vertically slidably in the frame, a clamp slidably mounted on the table comprising a pair of 30 shoes and a plate carried by the shoes, and springs to normally separate the plate from the shoes, a plunger slidably mounted on the head, a guide for the plunger so that it may have vertical movement, a spring to 35 force the plunger downwardly to press the members of the clamp together, means to engage the plunger when the head has reached the lower limit of its movement and cause the plunger to rise with the head, 40 means to release the plunger as the head reaches the upper limit of its movement, and a cam on the head to move the clamp when engaged by the plunger.

5. In a slitting machine for sheet metal, 45 the combination of a frame, a vertically movable head slidably mounted in the frame, a table supported by the frame, a longitudinally movable clamp mounted on the table and comprising upper and lower 50 members normally held apart between which

the sheet metal may pass, a vertically movable plunger mounted on the head, a guide for the plunger, a spring to force down the plunger against the upper member of the clamp when the head has moved downward in its operative stroke, said spring being compressed as the head descends after the plunger has engaged the clamp, means for moving the clamp while engaged by the plunger as the head is descending, a bolt to 55 engage the plunger when the head reaches the lower limit of its movement to cause the plunger to rise with the head, and a cam mounted on the frame and engaging the bolt and adapted to release the plunger as the 60 head reaches the upper limit of its movement.

6. In a slitting and bending machine for sheet metal, the combination of a table and a movable head, a clamp mounted on the 70 table, a plunger mounted on the head to engage the clamp to cause it to grip the sheet metal, a cam mounted on the head to engage and move the clamp and sheet metal, a spring to return the clamp, and 75 means mounted on the head to slit the sheet metal.

7. In a slitting and bending machine for sheet metal, the combination of a clamp to grip the sheet metal, positive means to move 80 the clamp and sheet metal, a spring to return the clamp, and a slitting device formed of a male and female portion, the male portion consisting of a flat shear and of a die having a transverse groove in line with 85 one side of the flat shear, so that long fins may be cut and bent from the sheet metal together with pairs of tongues which pairs of tongues remain attached to the sheet metal by means of narrow bars at their adjacent ends, said bars being in line with 90 said fins.

In testimony whereof I have signed this specification in the presence of two subscribing witnesses.

CONRAD REHBEIN.
